United States Patent Office

Des. 233,701
Patented Nov. 19, 1974

233,701

PRINTER

Gary R. Bluem, Minneapolis, Minn., assignor to Kroy
Industries, Inc., Stillwater, Minn.

Filed Jan. 30, 1973, Ser. No. 327,984

Term of patent 14 years

Int. Cl. D18—02
U.S. Cl. D64—11 R

Fig. 1

Fig. 2

Fig. 3

FIG. 1 is a perspective view of a printer showing my new design.

FIG. 2 is a top plan view, the cord being omitted for ease of illustration; and

FIG. 3 is a right side elevational view thereof.

The left side panel is a mirror image of the panel shown.

I claim:

The ornamental design for a printer, as shown and described.
